UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

HEELING-MACHINE.

1,330,900.

Specification of Letters Patent. Patented Feb. 17, 1920.

Original application filed March 3, 1916, Serial No. 81,873. Divided and this application filed April 24, 1918. Serial No. 230,428.

To all whom it may concern:

Be it known that I, JOSEPH H. POPE, a citizen of the United States, residing at Hamilton, in the county of Essex and State 5 of Massachusetts, have invented certain Improvements in Heeling-Machines, of which the following description, in connection with the accompanying drawings, is a specification, like reference characters on the drawings indicating like parts in the several 10 figures.

This invention relates to heeling machines, and more particularly to machines for attaching heels and top lifts to boots and 15 shoes, the present application being a division of application Serial No. 81,873, filed March 3, 1916.

An important feature of the present invention consists in a heel and toplift holder 20 provided with automatic mechanism for presenting a toplift in operative position after the heel has been nailed. As herein shown the holder is latched under spring tension prior to the heel attaching operation 25 and is released by the movement of a latching lever effected automatically after the attaching operation.

Another feature of the invention is comprised in a locking device for the loader 30 which is arranged to be controlled by the movement of the heel and toplift holder, the construction being such that when one load of nails has been delivered by the loader to the die plate of the machine, movement of the loader to deliver a second load 35 of nails is prevented until the heel and toplift holder have been moved to present a new heel in attaching position.

The invention further contemplates, in 40 combination with a nail block for supplying nails to the loader and mechanism which operates to advance the block, a locking device for such mechanism so arranged that movement of the block to deliver a second load of nails is prevented until the loader 45 has been moved to discharge the previous load, and a locking device for the loader which is controlled by the heel and toplift holder.

50 Another feature of the invention relates to improved mechanism for automatically measuring the work preliminarily to the power operation of the machine. As herein

shown a spring acting in compression is utilized as a source of motive power for the 55 measuring mechanism, the spring being coiled upon a tube and compressed during the power operation of the machine. This construction has proved to be superior to that heretofore employed wherein a tension 60 spring served as the source of motive power, both in point of durability and uniformity of action.

Still another feature of the invention consists in safety mechanism for preventing 65 either the measuring operation or the power actuation of the machine from taking place unless the jack has been moved into its operative position.

These and other features of the invention, 70 including important details of construction and combinations of parts will be best understood from the following description of a preferred embodiment of the invention, in connection with the accompanying drawings 75 illustrating the same, in which:—

Figure 1 is a view in front elevation of the well known Lightning nailing machine having the present invention embodied therein;

Fig. 2 is a detail view in perspective of 80 portions of the automatic measuring mechanism;

Fig. 3 is a view in perspective illustrating the heel and toplift holder operating mechanism and the safety locking devices, and 85

Fig. 4 is a detail view of a portion of the safety locking mechanism.

The machine frame 2 carries a stationary die plate 4 having a series of passages, as 90 shown in Fig. 3, for the drivers. Beneath the die plate is located the jack 6 upon which the lasted shoe is placed preparatory to the operation of the machine, the heel to be nailed being held in place upon the under 95 side of the die plate by clamping arms 7. A driver gang 8 is mounted in a cross head 10 carried at the upper ends of the two side rods 12 which are arranged to reciprocate in vertical bearings in the machine frame. 100 Secured to the lower ends of the side rods is a second cross head to which motion is imparted from the main shaft 18 through an eccentric strap 16.

To the front portion of the machine frame 105 2 is secured a stationary block 20 above

which is located the jack carriage support 22. The latter is arranged for a limited vertical movement in a vertical guideway formed partly in the machine frame and 5 partly by gibbs bolted thereto. The support 22 and all the parts carried thereby, including the jack, are moved vertically by power driven means when the machine is started and after the measuring operation has taken 10 place. For this purpose a pair of eccentric cams are mounted one in the stationary block 20 and the other in the support 22. These are oscillated by connections with the side rods during the initial part of the 15 downward movement of the cross head. In the present drawings the connecting mechanism is omitted for the sake of clearness, being substantially the same as corresponding mechanism disclosed in my prior Patent 20. No. 446,885, dated February 24, 1891.

Above the jack carriage support 22 and guided in the same ways as the latter, is located the jack carriage 24. The vertical position of the carriage is determined by a 25 large screw 26 threaded at its upper end into the carriage and resting at its lower head on the jack carriage support 22. The screw 26 is provided with elongated gear teeth meshing with a horizontally movable 30 rack 28 by the actuation of which the measuring operation is effected as will be presently described. The jack carriage 24 is formed at its upper side with substantially horizontal guideways in which slides the 35 jack 6. It will be understood that the jack is pulled forwardly in the ways to receive a shoe and then pushed rearwardly into operative position beneath the die plate preliminarily to starting the machine.

40 The mechanism thus far described is substantially similar to the corresponding mechanism of the well known Lightning nailing machine. Such portions of the machine as are not herein specifically described are 45 similar to the corresponding parts shown in my prior patent above identified.

The measuring operation is effected by rotating the screw 26 to elevate the jack and thus bring the two parts of the work into 50 engagement, pressing them together with a predetermined measuring pressure independently of the thickness of the work. The source of motive power for actuating the rack 28 in carrying out the measuring operation consists in a long spring 42 acting 55 in compression. The spring is arranged to encircle a tube 50, see Fig. 2, which is secured at its upper end to a bracket 52 bolted on a vertically movable bar 54. The tube 60 50 has a flange 48 at its lower end upon which the spring 42 rests. Loosely mounted to telescope within the tube 50 is a rod 49 which is secured at its lower end to the machine frame and provided at its upper end 65 with a cross pin projecting outwardly

through a slot in the tube 50 and seated in a collar 46 bearing upon the upper end of the spring 42.

It will be seen that, when the two telescopic members 49 and 50 are elongated by 70 the upward movement of the tube 50, the spring 42 is compressed between the flange 48 and the collar 46. This takes place when the bar 54 is moved upwardly by the power of the machine, the bar being latched in its 75 upper position with the spring 42 held under compression.

The bar 54 is guided for vertical movement at its upper end by passing through a vertical opening in a box 56 rigidly bolted to the left side rod 12. At its lower end the bar 54 is pivotally connected to one arm of a triangular lever 30 pivoted upon a stud 58 projecting from the stationary block 20. The bar 54 extends below its point of connection with the lever 30 and is slotted to receive a spring 60 which permits lost motion to occur between the bar 54 and the lever 30 when the rod is moved upwardly by the power of the machine as will presently appear. The lever 30 is connected through a short link 29 to the rack 28. It will be apparent that when the bar 54 is elevated and the spring 42 compressed the rack 28 will be moved to the right and the 90 screw 26 turned in the direction to lower the jack 6. On the other hand, when the bar 54 is tripped, and the spring 42 permitted to expand and move the bar 54 downwardly, the rack 28 will be moved to the left through 100 the connections described and the jack elevated to effect the measuring operation.

The bar 54 is provided near its upper end and upon its rear side with a catch or shoulder 62. The box 56 carries a pivoted dog 105 64 which is arranged to engage the shoulder 62 in the upward movement of the side rod carrying the bar 54 upwardly and holding it in the position shown in Fig. 1 with the spring 42 under compression. The starting lever 66 of the machine has connections with the dog 64 such that in its initial movement the dog is disengaged from the shoulder 62 whereupon the bar 54 is free to move downwardly under the actuation of the spring 42 thus effecting the measuring operation as above outlined.

The starting lever 66 is connected through a treadle rod 72 to a treadle 70 by which the operator initiates the measuring operation. The starting lever 66 is also connected to the main clutch of the machine by mechanism not here illustrated but which corresponds to that of my earlier patent above identified. The arrangement is such that 125 the continued depression of the treadle, after the measuring operation has been effected, throws the clutch and starts the power operation of the machine.

In the usual operation of the machine 130

the bar 54 is elevated by the upward movement of the side rod but it may happen that it is desired to effect this operation without starting the machine or to lift the 5 bar 54 temporarily to depress the jack and thus afford opportunity to adjust the position of the heel or shoe before the attaching nails are driven. To this end a lever 44 is mounted upon the stud 58 of the lever 30 and is so arranged that it can be swung upwardly to turn the lever 30 in a clockwise direction by coming into engagement with the pivot pin by which the lever 30 is connected to the bar 54. The inner end of the 10 lever 44 normally projects beneath the pin 21 set in the block 20 which acts as a stop for the lever 30 and also for the lever 14. During the normal operation of the machine the lever 44 remains at rest in the position 15 shown in Fig. 1, being operated only when occasion demands.

In order to safeguard the operator by preventing the inadvertent starting of the machine before the jack has been moved inwardly to position the work properly, a 20 safety lever 74 is pivotally mounted on an arm projecting from one of the gibbs of the machine frame and arranged to stand normally with its inner arm in the path of the 25 jack 6. The outer and shorter arm of the lever 74 extends under a locking piece 76 rigidly secured to the upper end of the treadle rod 72. A spring pressed pin 78 bears upon the rear side of the inner arm of 30 the lever 74 and swings it normally into locking relation with the piece 76 as shown in Fig. 2. When the jack, however, is pushed inwardly into operative position it 35 encounters the lever 74 and swings its outer end forwardly into a position in which the locking piece 76 will clear it when the treadle is depressed.

The position of the shoe upon the jack is controlled from front to rear by a back 40 gage 80 adjustably mounted in the machine frame beneath the die plate 4. The back gage 80 is carried by a horizontally disposed screw having a beveled gear 82 secured thereto and arranged to mesh with a 45 beveled gear 84 upon the rear end of a shaft 86 having a knurled head at its outer end. The shaft 86 is journaled in bearings formed in a collar 88 which surrounds the right side rod and rests upon the upper part of 50 the machine frame. The shaft extends obliquely inwardly to the back gage, its head or hand nut being located conveniently within the reach of the operator.

An oscillating heel and toplift holder is 55 pivotally mounted at the rear of the die plate 4 and arranged to present the heel and toplift blanks successively in position beneath the driver passages. The holder includes a pair of toplift clamping arms 90 60 and a pair of heel engaging arms 7. A

spanker plate 91 is disposed above the toplift clamping arms 90 and arranged to be interposed between the toplift and the lower face of the die plate during the spanking operation. The movement of the heel and 70 toplift carrier is controlled by mechanism which will now be described. In initial position the holder is positioned with the heel clamping arms 7 beneath the die plate and the top lift clamping arms 90 projecting toward the right hand side of the machine. The holder is provided with an arm 92, see Fig. 2, extending rearwardly and carrying a downwardly projecting rod 94 connected at its lower end to a horizontally extending 75 rod 96. The rod 96 has an adjustable turn buckle in its length and is pivotally connected to the rear end of a lever 98 pivotally mounted on a stud 100. The stud 100 projects downwardly from a bracket 102 80 carried by the collar 88. The stud 100 is encircled by a torsion spring 104 which tends normally to throw the rear end of the lever toward the right and, through the 85 connections above described, to turn the toplift clamping arms 90 into position beneath the die plate 4. This action of the spring 104, however, is prevented during a portion of the cycle of the machine by a latch lever 98 90 pivoted upon a horizontal stud 108 to 95 the frame of the machine. The lever 106 has a horizontal arm which is arranged to engage with the flat side of a pin 110 set in the handle or front end of the lever 98. The lever 98 is made in two pieces which 100 are arranged to have a limited relative movement in a horizontal plane. The forward end of the rear part of the lever 98 is provided with a cased spring 112 which tends normally to swing the handle end of 105 the lever inwardly when permitted to do so.

The latching lever 106 is lifted automatically to disengage the pin 110 during the upward movement of the side rod 12 at the conclusion of the nail driving operation. 110 To this end the downwardly extending arm of the latch lever 106 is provided with a pivoted switch cam 114 with which cooperates a pin 116 set in a collar 118 fast upon the side rod 12. The cam 114 is so 115 disposed that when the side rod and the pin 116 are moved downwardly the cam piece will be displaced inwardly at its lower end without affecting the position of the latching lever 106. In the upward movement of 120 the side rod, however, the pin 116 encounters the other face of the cam 114 and acts to swing the latching lever 106 in a contra-clockwise direction thus elevating its horizontal arm and releasing the pin 110 in 125 the lever 98. This movement of the lever 106 takes place in opposition to a spring 120 interposed between it and a post on the bracket 102.

As soon as the arm of the latching lever 130

106 is elevated the forward or handle end of the lever 98 moves inwardly carrying the pin 110 beneath the arm of the lever and permitting the lever 98 to swing outwardly 5 at its rear end thereby turning the heel and toplift holder to carry the toplift clamping arms beneath the die plate. This feature of construction is important in that the oscillation of the latching lever is rapidly 10 effected and if the catch were not promptly moved out of range of the lever 106 it would be caught again by the lever 106 before the slower moving holder would permit it to move.

15 In order to cushion the action of the holder, dash pot mechanism is provided including a tube 122 set in the machine frame and having its plunger connected by a link 124 to an adjustable clamping piece 126 fast 20 upon the rod 96.

The attaching nails are supplied to the die block by a loader block 130 carried in an oscillating loader arm 132 pivotally mounted upon the right side rod 12. The 25 arm 132 of the loader block extends outwardly beyond the block 130 and is provided with a handle 134 by which the operator swings it from the nail receiving position to nail delivering position above the 30 passages in the die block. A plate covers the lower face of the loader block 130 and prevents the nails from falling out of it during its movement into delivering position.

35 Safety mechanism is provided for preventing a second movement of the nail loader into delivering position after the passages in the die block have once been supplied with nails and before these nails have 40 been driven. As herein shown, this mechanism is controlled by the movement of the heel and toplift holder. To this end there is provided upon the loader arm 132 a block 136 having a notch in its upper face which, 45 in the nail receiving position of the loader arm, is disposed beneath a locking pin 138 mounted for vertical movement in bearings carried by a stationary bracket 140. When the locking pin 138 is lowered into the notch 50 in the block 136 the loader arm is locked positively against movement from nail receiving position. The locking pin 138 is connected to a flexible wire 142 inclosed in a spring tube 143, see Fig. 3, which extends 55 to an angular bracket 144 located at the rear of the die plate 4 above the heel and toplift holder. The bracket 144 is provided with bearings for a vertically movable rod 146, see Fig. 4. The rod 146 is connected to 60 one arm of a bell crank lever 148 pivotally mounted upon an ear on the bracket 144. The downwardly extending arm of the lever 148 carries a pivoted tripping piece 150. The tripping piece 150 is arranged to yield 65 when moved in one direction, *i. e.*, up-

wardly, but to engage a stop pin on the lever 148 and swing the latter when it is moved in the opposite direction.

The tripping piece 150 is operated by a tripping plate 152 secured to the rear side 70 of the heel and toplift holder. A spring encircles the rod 146 beneath the arm of the lever 148, normally lifts the rod and through the flexible connection depresses the locking pin 138, the supposition being that one load 75 of nails has now been delivered to the die plate. It is therefore impossible to move the loader arm until the locking pin 138 has been lifted and this is effected through the mechanism above described by swinging the 80 heel and toplift holder, first to carry the toplift holding arms 90 into position beneath the die plate, and then in the opposite direction to carry the heel holding arms 7 into operative position. In these two 85 movements it will be seen that the tripping plate 152 is first carried beneath the pivoted tripping piece 150 while the latter moves idly and is then moved reversely engaging the tripping piece 150 and swinging the 90 horizontal arm of the lever 148 downwardly, thus lifting the locking pin 138 as will be apparent. The loader arm is displaced immediately so as to carry the locking block 136 out from beneath the locking pin 138. 95 This is effected by a spring pressed plunger carried in the lower end of a ratchet lever 156 the purpose of which will be presently described.

The bracket 102 carries a pair of vertical 100 rods 160 which carry at their upper ends a stationary frame 162 shaped to constitute a horizontal guideway. Inclined bracing rods 164 extend between the rods 160 and the forward end of the frame 162. The frame 162 has parallel flanges upon which slides a carriage 168 having a handle 170 arranged to bridge its forward ends. The carriage is shaped to receive a nail carrying block provided with parallel rows of perforations to receive nails, and the block is held in the carriage by suitable clamping means. The nail supplying block is not shown herein, as it forms no part of the present invention, but is shown, described and claimed in application, Serial No. 81,873, heretofore mentioned, to which reference may be made for a full understanding of its details. The carriage 168 and the nail block therein are moved intermittently 110 forward to discharge one row of nails after another to openings in the frame 162 which are caused to register successively with rows of openings in the nail carrying block. As herein shown, this is effected by mechanism 115 operated by the loader arm 132. The carriage 168 is provided at one side of its lower face with a rack 202, and the ratchet lever 156 is pivotally mounted on a bracket 204 secured to one of the rods 160 and carries at 120 130

its upper end a dog 206 which coöperates with the teeth of the ratchet 202. The bracket 204 is provided with a rearward extension having a casing 208 for a spring 5 pressed pin which tends normally to throw the lower end of the ratchet lever forward. When the loader arm is moved outwardly into nail receiving position, as shown in Fig. 3, it encounters the lower end of the ratchet lever 156, swinging the same rearwardly and advancing the carriage 168 that distance required to discharge a load of nails from the nail block into the openings in the carriage. The nails pass from these 10 openings through the tubes 184 to the foot plate 252, and through holes in this plate to the loader. When the loader arm 132 has been moved to the end of its path it is locked in position by the locking pin 138 15 as already explained.

In addition to the safety mechanism already described, which prevents movement of the loader arm 132 before the heel and toplift holder has been turned to position 20 a heel for nailing, there is also provided safety mechanism for preventing movement of the ratchet lever 156 to advance the nail carrying block and discharge a row of nails until after nails already supplied to the 25 loader have been delivered to the nail block 4. To this end the loader arm is provided with a cam 220 which is arranged to co-operate with a pin 222 set in a slide bar 224 for causing horizontal reciprocation of the 30 bar. The bar 224 carries upon its rear side a pin 226 arranged to engage a bell crank lever 228 pivotally mounted in the bracket 144 and of similar construction to the lever 148 already described and shown in Fig. 4. 35 The lever 228 has a flexible connection through the spring tube 230 to a locking pin 232 mounted to slide in the bracket piece 204 and arranged to enter a socket formed in the side of the ratchet lever 156. The arrangement of the parts above described is 40 such that the locking pin 232 is withdrawn from its socket only when the slide bar 224 is moved to its extreme left hand position as shown in Fig. 3 by movement of the loader 45 arm sufficient to discharge the nails carried thereby to the die block.

The operation of the machine will be apparent from the foregoing description and may be outlined as follows: The machine 50 comes to rest with its elements in the positions shown in Fig. 1, except that the toplift clamping arms 90 instead of the heel holding arms 7 are located beneath the die block and the lever 98 occupies its inner or 55 left hand position. As shown in Fig. 1 the bar 54 has been moved upwardly and latched in position with the spring 42 under compression. The operator first inserts a toplift between the arms 90 and then swings 60 the lever 98 outwardly thus bringing the

heel holding arms 7 beneath the die block and latching the lever 98 by the lever 106 in the position shown. This movement of the heel and toplift holder releases the locking stud 138 freeing the loader arm so that 70 the operator may now swing it inwardly to discharge the attaching nails to the die block. This movement of the loader arm retracts the locking pin 232 to free the ratchet lever 156 and in the reverse movement of the loader arm the lower end of the lever 156 is encountered and the carriage 168 moved forwardly to discharge the nails from a row of the holes in the nail carrying block into the nail passages through 80 which they pass to the loader arm. The shoe is then placed upon the jack 6 and then moved rearwardly to carry the heel seat of the shoe beneath the heel to be attached and in this movement of the jack the safety 85 lever 74 is moved to release the starting mechanism. The operator next depresses the treadle 70 which first moves the dog 62 to release the bar 54 permitting the spring 42 to expand and elevate the jack to effect the measuring operation. Continued depression of the treadle 70 trips the main clutch of the machine whereupon the jack carriage support is elevated to apply an increased pressure to the work, the drivers 90 acting to drive the attaching nails and the cross head is then elevated to its initial position. During this latter movement the bar 54 is again elevated and the latching lever 106 is oscillated to release the lever 98 and 95 permit the heel and toplift holder to swing the toplift into position above the attached heel. Both of the locking studs 232 and 138 are now operative so that it is impossible for the operator to move the loader arm. The 100 treadle 70 is again depressed, the work measured as before and the toplift finally spanked in place whereupon the completely heeled shoe may be removed from the machine in readiness for a repetition of the 105 cycle.

Having thus described my invention, I claim as new and desire to secure by Letters Patent of the United States:

1. A machine of the class described, having, in combination, a movable heel holder, a loader, and a locking device for the loader including a pin, a flexible operating element connected to the pin, and means controlled by the holder for moving longitudinally the 115 flexible operating element.
2. A machine of the class described, having, in combination, a relatively movable work support and die plate, and automatic measuring mechanism including a coiled 120 spiral spring and means for holding said spring under compression, and for thereafter permitting the spring to expand and elevate the work support to effect the measuring operation.

3. A machine of the class described, having, in combination, a relatively movable work support and die plate, and automatic measuring mechanism including a tube arranged to be moved in one direction by the power of the machine, and a spring coiled about the tube and compressed when the tube is so moved, said spring effecting the measuring operation.
- 10 4. A machine of the class described, having, in combination, a relatively movable work support and die plate, and automatic measuring mechanism including telescopic members and a spring coiled about said members and arranged to be compressed when they are elongated and to effect the measuring operation by contracting said members.
- 15 5. A machine of the class described, having, in combination, work pressing members including a horizontally movable jack, automatic measuring mechanism including a starting lever, and means for preventing the operation of the starting lever when the jack is out of work pressing position.
- 20 6. A machine of the class described, having, in combination, a heel and toplift holder, a lever for moving the holder in one direction, a spring for moving the holder in the other direction, a latching lever carrying a switch cam, and a reciprocating actuating member constructed and arranged to move the switch cam idly during its reciprocation in one direction and to move the latching lever through the switch cam during its reciprocation in the other direction.
- 25 7. A machine of the class described, having, in combination, a heel and toplift holder, a lever connected to the holder and having relatively movable parts one of which carries a latch piece, and an automatically operated latch lever, the latch piece carrying part of the lever being movable independently of the holder.
- 30 8. A machine of the class described, having, in combination, a jack, a back gage arranged to engage a shoe supported on the jack for determining its position relatively to a heel to be attached to the shoe, and adjusting means for the gage including a shaft extending forwardly and having a hand wheel located at one side of the shoe.
- 35 9. A machine of the class described, having, in combination, a vertically movable jack for a shoe, a pivotally mounted holder for heels and toplifts, means tending normally to swing the holder to toplift presenting position, manually operated means for moving and latching the holder in heel presenting position, and automatic means for releasing the holder simultaneously with the movement in one direction of the jack.
- 40 10. A machine of the class described, having, in combination, a driver head and side rods, a pivoted holder for heels and toplifts,
- 45 and a device for latching the holder under spring tension arranged to be operated by one of the side rods for releasing the holder.
- 50 11. A machine of the class described, having, in combination, a driver head and side rods, a pivoted holder for heels and toplifts, a two-part lever and an oscillatory latching device coöperating to hold the holder under spring tension, and means for moving one part of the lever out of range of the latching device when the latter is moved to releasing position.
- 55 12. A machine of the class described, having, in combination, a jack movable horizontally to and from operative position, automatic measuring mechanism, manually-controllable devices for initiating the operation of said mechanism, and means for preventing the operation of said devices while the jack is out of its operative position.
- 60 13. A machine of the class described, having, in combination, heel attaching mechanism, a jack movable to and from operative position, automatic measuring mechanism, means for initiating the operation of said mechanism and for starting the machine, including a single controlling member, and means for preventing the operation of said member while the jack is out of its operative position.
- 65 14. The combination of heel attaching mechanism, a jack movable into and out of operative position, automatic measuring mechanism, a detent for preventing the operation of the measuring mechanism, a manually operable member for starting the machine and for tripping the detent, and means for obstructing movement of said member until the jack is moved into operative position.
- 70 15. A machine of the class described, having, in combination, a movable nail block, a movable holder for heels to be nailed, means for advancing the nail block to deliver successive loads of nails, and a locking device for said means arranged to be controlled by the movement of the holder.
- 75 16. A machine of the class described, having, in combination, a movable nail block, a loader, a heel holder, means for advancing the nail block to deliver successive loads of nails to the loader, and a pair of locking devices for said means, one arranged to be controlled by the movement of the holder and the other by the loader.
- 80 17. A machine of the class described, having, in combination, nail supplying means, a loader, a lock for the loader, and a movable heel holder arranged to control said lock.
- 85 18. A machine of the class described, having, in combination, a movable nail block, a loader, means operated by the loader for advancing the nail block to deliver successive loads of nails, a movable heel holder,
- 90 95 100 105 110 115 120 125 130

and a locking device operating on the loader and controlled by the holder.

19. A machine of the class described, having, in combination, a movable nail block, 5 a feeding lever for advancing the block to deliver successive loads of nails, a loader, a heel holder for the heel to be attached, a lock for the feeding lever controlled by the loader so that the nail block can be advanced 10 only after a load of nails has been discharged by the loader, and a lock for the loader controlled by the holder so that the loader can be moved only after a heel has been presented.

15 20. In a heeling machine, the combination with nailing mechanism, of mechanism for transferring nails to the nailing mechanism, a movable work-engaging member coöperating with the nailing mechanism, and 20 means controlled by said member for preventing the delivery of more than one charge of nails for a single operation of the nailing mechanism.

21. In a heeling machine, the combination 25 with a nail block, of a movable loader mechanism for delivering nails to the block, a movable holder coöperating with the nail block, and means controlled by the holder for limiting the movement of the loader 30 mechanism.

22. In a heeling machine, the combination 35 with nailing mechanism, of mechanism for transferring nails to the nailing mechanism, a work-engaging member coöperating with the nailing mechanism in a plurality of positions, and means controlled by the work-engaging member for preventing the delivery of more than one charge of nails until 40 said member has occupied a plurality of positions.

23. In a heeling machine, the combination 45 with a nail block, of a movable loader mechanism for delivering nails to the block, a movable holder coöperating with the nail block, and means controlled by the holder for preventing the coöperation of the loader and block before the nails delivered have been discharged from the block.

24. In a heeling machine, nailing mechanism, nail loading mechanism, a swing plate having heel and top lift holders movable into coöperation with the nailing mechanism, and a stop movable with the swing plate, said stop coöperating with the loader mechanism when the top-lift holder co- 55 operates with the nailing mechanism and being ineffective when the heel holder co- operates with the nailing mechanism.

25. In a heeling machine, nailing mechanism, nail distributing mechanism, mechanism for receiving nails from the distributing mechanism and transferring them to the nailing mechanism, the movement of the transfer mechanism controlling the distributing mechanism, and means for delaying 60 the operation of the distributing mechanism until a full delivery movement of the transfer mechanism has been made.

26. In a heeling machine, nailing mechanism, nail distributing mechanism, mechanism for receiving nails from the distributing mechanism and transferring them to the nailing mechanism, a member movable with the transfer mechanism for initiating 70 the operation of the distributing mechanism, 75 and a member connected to the distributing mechanism with which said initiating member contacts actively only after the transfer mechanism has completed its delivery movement.

27. In a heeling machine, nailing mechanism, nail distributing mechanism, mechanism for receiving nails from the distributing mechanism and transferring them to the nailing mechanism, means for preventing 85 the delivery of more than one charge of nails to the nailing mechanism between successive operations thereof, and means for preventing delivery of more than one charge of nails to the transfer mechanism between 90 successive deliveries to the nailing mechanism.

In testimony whereof I have signed my name to this specification.

JOSEPH H. POPE.
